FOLDABLE CRATE

Bemis Huggins, Humboldt, Tenn.

Application September 27, 1934, Serial No. 745,784

8 Claims. (Cl. 217—48)

This invention relates to that class of structures found in a special sub-division of the prior art devoted to collapsible boxes and so-called folding and knock-down crates for the accommodation and transportation of berry boxes and the like.

Being generally familiar with this particular line of endeavor and having studied the types of crates now offered to the trade, I have discovered noteworthy defects in the construction such as subjects these crates to undue and limited utility. It has been observed that insecurity and lack of strength found in present-day types of foldable crates gives rise to complaints and disapproval by many users, and this is to be expected when one takes into consideration the rough handling by inconsiderate employees. The type of crates to which I allude are those wherein the side and end walls are hingedly connected together by means capable of allowing said parts to be collapsed into compact form for shipment and subsequent expeditious erection.

Striving for economy of manufacture and quantity output, manufacturers of crates of this type have resorted to the use of relatively fragile hinge constructions. Without attempting to depart from the realm of simplicity and economy, I have discovered the need for a new type hinge arrangement and have accomplished this by the adoption and use of the particular means to be hereinafter described. Being ingenious and somewhat of an innovation, the improved hinge and cover-retaining means which I have perfected, will be the principal subject of the following description.

In reducing the invention to practice, I have found it expedient and practicable to resort to the adoption and use of a two-part assemblage wherein one part is in the nature of a staple which serves as a hinge or joining device between the walls of the frame, the other part being in the nature of a disk having a plurality of functions to be hereinafter described in detail.

Other features and advantages will become more readily apparent from the following description and drawings.

In the accompanying drawings wherein like numerals are employed to designate like parts throughout the same:

Fig. 1 is a top plan view of a crate constructed in accordance with my ideas and embodying the unique hinge and cover retention means.

Fig. 2 is a side elevational view of the arrangement depicted in Fig. 1.

Fig. 3 is a fragmentary view taken on an enlarged scale showing the merits and construction of the improved means, the section being on the line 3—3 of Fig. 1.

Fig. 4 is an enlarged plan view showing in detail the double-acting disk elements forming an essential feature of the invention.

Referring to Fig. 1, it will be observed that the collapsible or frame portion of the crate comprises a pair of spaced parallel longitudinal side walls 5 joined together through the instrumentality of transverse end walls 6. These may be of customary slat construction. The meeting ends of the respective walls 5 and 6 are hingedly connected together and hinges and retaining means in the present drawings constitute the novelty hereinafter claimed. It is to be pointed out however, that in this type of crate, the parts 5 and 6 are simply joined together by hinge means which allows them to be folded into compact relation. This tends to permit the top and bottom to be inserted as a means for maintaining the parts 5 and 6 in box-forming relationship. The bottom and top will be substantially identical or approximately so in construction. In the drawings, I have simply shown the top or lid and this is designated by the numeral 7 and comprises slats or the like joined together by transverse cleats 8 having extended end portions 9 and outwardly beyond the cleats are the customary cross pieces 10 which serve essentially as reinforcing members. It is understood, however, that it is not the crate construction but rather the hinge construction which forms the principal novelty. Before introducing the hinge and retaining means, I would point out that the numerals 11 and 12 designate longitudinal and transverse rails forming integral parts of the side and end walls. In the present arrangement, the adjacent ends of the rails 11 and 12 are formed with holes to accommodate the hinge and connecting means.

Inasmuch as the hinge and retaining means is the same at each corner as well as at the top and bottom of the complete crate, it is believed sufficient to describe a single means, that is the complete unit which is utilized as a device to serve as connecting and hinge means as well as retaining means for the cover 7. I direct attention therefore to Fig. 4 wherein it will be observed that the means embodies a disk 13 of appropriate material and proportions. In accordance with the present inventive conception, this disk is provided with a series of apertures or holes 14. In practice, I may provide either a single pair of 50

holes or four holes arranged at equidistant circumferentially spaced points. These holes are adapted to register with the bores or passages which are formed in the adjacent ends of the 5 rails 11 and 12. The latter holes are intended to accommodate the arm portions 15 of the staple 16. This is a wire staple relatively small and of appropriate gauge metal. By registering a pair of the staple openings 14 with the bores in the 10 rails, it is evident that the arms of the staple can be dropped down through these registering passages to effect a hinge joint and connection between the rails. This allows the bight portion 17 to rest on the disk and permits the terminals 15 or the free ends of the arms 15 to be bent laterally or clinched as at 18 for secure maintenance. It follows therefore that the staple actually straddles the adjacent bored ends of the rails to join these together hingedly in an obvious manner. 20 The disk, however, is so arranged that it serves as a wear plate or washer for the bight 17 and the adjacent portions of the arms 15. Then too, the disk is of sufficient diameter as to extend beyond the corner, that is, inwardly beyond the 25 corner of the crate when it is set up as shown in Fig. 1 so as to function as a keeper for the cover. Or stated otherwise, the corner portions of the cover can be placed underneath the projecting portions of the various disks so as to permit the 30 cover to be securely held in place through the instrumentality of these disks.

By using a disk, it has a twofold purpose, that is, it serves as a washer as well as a keeper or retaining element. Not only this, the disk does not 35 project outwardly beyond the edges of the rails to interfere with the safe handling of the crate as a whole. Moreover, the marginal edge formation of the disks facilitates placement of the corner portions of the crate cover in a position to be 40 securely held in place. Heretofore, similar hinge arrangements have been utilized for somewhat the same purposes, but none are so unique and practicable as the arrangement just described.

By way of contrast and comparison with similar prior art devices it will be observed that this 45 structure provides a collapsible crate wherein the crate when folded assumes a position so that the inner ends of the two side walls overlap, whereas the end walls overlap the remaining portions of 50 the side walls. This is known in the field as a "jack-knife" type of foldable crate as distinguished from the more compact arrangement disclosed in the J. J. Dahlstrom folding crate depicted in Patent 1,120,693. Or stated otherwise 55 my crate when folded occupies the more rigid folded arrangement disclosed in the O. P. Wilson et al. Patent 1,869,292. The arrangement which I have employed, however, retains all of the flexible features of Dahlstrom, and provides the 60 rigidity of O. P. Wilson et al. and, therefore, is characterized by an arrangement which transcends in importance and practicability these and similar prior art structures which renders it susceptible of unqualified endorsement by the trade.

65 It is thought that persons skilled in the art to which the invention relates will be able to obtain a clear understanding of the invention after considering the description in connection with the drawings. Therefore, a more lengthy description is regarded as unnecessary.

70 Minor changes in shape, size and rearrangement of details coming within the field of invention claimed may be resorted to in actual practice, if desired.

I claim:

1. In a knock-down crate, a collapsible crate frame embodying spaced parallel side walls and the complementary end walls interposed between the end portions of said side walls, all of said walls being provided with reinforcing rails whose end portions are adapted to come together in abutting relationship when the crate is set up for use, and a plurality of duplicate hinge forming cover retaining units, there being a single unit 10 for each corner portion of the frame structure, and said unit embodying a U-shaped wire staple arranged to bridge the space between the adjacent abutting ends of the complementary rails, said rails having bored passages and the arm portions 15 of the staple extending through and beyond said passages with the free ends clinched against the underside of the rail-ends, the length of the bight portion of the staple being such as to be confined 20 within the spaces defined by the width of said rails, and a cover retaining clip attached to said staple, said clip being adapted to project into the frame in a manner to overlie the cover and serve as a keeper therefor.

2. In a knock-down berry box crate, a foldable 25 crate frame embodying spaced parallel side walls and complementary end walls, all of said walls being provided with horizontal reinforcing rails whose end portions are adapted to come together in right angular abutting relationship when the 30 crate is set up for use, and a plurality of duplicate hinge forming cover retaining units, there being a single unit for each corner portion of the frame, and said unit embodying a U-shaped wire 35 staple having its bight portion arranged to bridge the space between the adjacent abutting ends of the complementary rails, said rails having bored 40 passages and the arm portions of the staple extending through and beyond said passages with the free ends clinched against the underside of the rail-ends, the length of the bight portion of the 45 staple being such as to be confined within the spaces defined by the width of said rails and serving primarily as a comparatively rigid hinge connection between the rail-ends, said unit also including a wear plate having apertures through 50 which the arms of the staple pass with the bight portion resting in contact with the underlying segmental portion of the plate allowing said plate to serve as a wear resisting and reinforcing member.

3. In a knock-down crate construction of the 55 class described, a longitudinal side wall, a companion transverse end wall disposed at right angles thereto and in abutting relation therewith, a plate resting on the upper edges of the corner forming portions of said walls, said corner portions of the wall being formed with staple holes, and said plate having staple openings in registry therewith, a staple having its bight portion superimposed upon said plate and its arm portions extending through the openings in the plate and holes in said walls and secured in place, and said plate having a predetermined marginal portion 60 thereof projecting inwardly beyond the walls to serve as a reinforcing member, as a wear plate, and as a keeper for the corner portion of a complementary crate top and/or bottom as the case may be.

4. In a knock-down crate construction of the 70 class described, a substantially rectangular foldable crate frame embodying spaced parallel side walls and companion end walls interposed between the end portions of said side walls, and a 75

plurality of independent hinge forming and cover retaining devices cooperable with the abutting ends of said walls, said walls including horizontal rails having their adjacent portions arranged in abutting relation and formed with staple holes, each device including an apertured disk resting upon the upper faces of said rails, the apertures of the disk being registerable with the staple holes, and a complemental staple associated with the disk, said staple being confined within the limits of the perimeter of the disk, having its bight portion superimposed upon and underlying segmental section of the disk and its arm portions extending through the apertures and aforementioned staple holes, the free ends of the arms being clinched against adjacent surfaces of the rails to hold the device in position in a manner so that a limited segmental portion of the disk projects inwardly into the 20 crate frame to serve as a keeper for an adjacent corner portion of the crate lid or cover.

5. As a new article of manufacture, a two-part fixture designed to serve as a foldable crate frame hinge as well as a cover retaining device, 25 said fixture comprising a metal disk of a predetermined diameter provided with a series of staple apertures arranged at equidistant circumferentially spaced points, said apertures being selectively usable in pairs and being adapted for 30 selective alignment with staple openings in adjacent portions of the crate frame, and a relatively small hinge forming staple, said staple being of U-shaped construction and the arms thereof being adapted to extend selectively 35 through a predetermined pair of said apertures so that the bight portion rests upon the disk, said disk serving as a wear and end thrust plate for the staple, as a brace for the arms of the staple, a reinforcing member for the complemental corner adjacent portion of the crate 40 frame, and a predetermined sector of the disk serving, when in use, as a keeper for an adjacent corner portion of a lid or closure for the crate frame.

45 6. In a knock-down berry box crate construction of the class described, a substantially rectangular foldable crate frame embodying spaced parallel side walls and companion end walls interposed between the end portions of said side walls, and a plurality of independent hinge forming and cover retaining devices cooperable with the abutting ends of said walls at the corner portions of the crate frame, said walls being provided on their upper and lower portions with 50 horizontal rails having the adjacent end portions arranged in separable abutting relation and

5 formed at predetermined points spaced inwardly from said ends with bored holes, each device including an apertured disk resting upon the adjacent faces of the complemental rail-ends, the apertures of the disk being aligned with the adjacent holes, and a double prong disk fastener and hinge forming element, the prongs thereof passing through predetermined apertures in the disk and through said holes, the free ends of 10 the prongs being secured to the rails, whereby to hingedly connect the walls in assembled foldable relationship, and to fasten the disk down against the underlying surfaces of the rails so that a segmental portion of the disks rests in a 15 shiftable position on said rails, with the diametrically opposed segmental portion projecting into the frame to serve as a keeper.

7. In a folding crate structure, a collapsible rectangular frame having a plurality of sides with the ends of said sides arranged in right 20 angular foldable corner-forming relationship, a connecting and hinge-forming staple having one leg rotatably anchored in the end portion of one side and the other leg fastened in the end portion of the adjacent side in a manner so that 25 the bight portion of the staple is limited to a position to bridge across the existing gap in the line of contact of said ends, and a corner reinforcing and cover-retaining plate carried by the aforesaid corner-forming end portions of said 30 sides to maintain the sides in a uniform plane during the folding operation, a portion of said plate projecting inwardly beyond the inner surfaces of said sides to function as a crate closure retainer.

35 8. In a folding crate structure, a collapsible rectangular frame having a plurality of sides with the ends of said sides arranged in right angular foldable corner-forming relationship, a connecting and hinge-forming staple having one leg rotatably anchored in the end portion of one side and the other leg fastened in the end portion of the adjacent side in a manner so that 40 the bight portion of the staple is limited to a position to bridge across the existing gap in the line of contact of said ends, and a corner reinforcing and cover-retaining plate mounted for limited shifting movement on the aforesaid end portions of said sides within the vicinity of 45 said staple, whereby to keep the sides in line 50 during the folding operation, and said plate extending inwardly beyond the adjacent surfaces of the sides to serve as a keeper for an underlying corner portion of a crate cover.

55 BEMIS HUGGINS.
